DESIGN FOR A CHAIN

Lawrence E. Baer, Attleboro, Mass., assignor to
The Baer & Wilde Co., Inc., a corporation of
Massachusetts

Application October 27, 1933. Serial No. 49,579

Term of patent 7 years

To all whom it may concern:

Be it known that I, LAWRENCE E. BAER, a citizen of the United States of America, residing in Attleboro, County of Bristol, State of Massachusetts, have invented a new, original, and ornamental Design for a Chain, of which the following is a specification, reference being had to the accompanying drawing, forming a part thereof.

Fig. 1 is a front elevation of a chain, showing my new design; Fig. 2 is a top plan view, and Fig. 3 is a perspective view of the same on a reduced scale.

I claim:

The ornamental design for a chain, substantially as shown and described.

LAWRENCE E. BAER.
